INVENTOR

Joseph Bennor,
BY
Joshua Pusey,
ATTORNEY

UNITED STATES PATENT OFFICE.

JOSEPH BENNOR, OF MACON, GEORGIA, ASSIGNOR TO UNIVERSAL PACKAGE-TIE DEVICE COMPANY, OF SAME PLACE.

DESIGN FOR A PACKAGE-TIE BUTTON.

SPECIFICATION forming part of Design No. 34,128, dated February 26, 1901.

Application filed January 28, 1901. Serial No. 46,142. Term of patent 14 years.

To all whom it may concern:

Be it known that I, JOSEPH BENNOR, a citizen of the United States, residing at Macon, Bibb county, in the State of Georgia, have invented and produced a new and original Design for Package-Tie Buttons, of which the following is a full, clear, and exact description, reference being had to the accompanying drawings, of which—

Figure 1 is a plan view of a package-tie button, showing my new design. Fig. 2 is a side elevation. Fig. 3 is a section on line xx , Fig. 1.

As shown in the drawings, the leading feature of my design consists of a dome-shaped portion A, from the base of which extends a

rim portion B, flat on the bottom at C and turned up at D at an angle, thus forming a circular groove E between said dome and rim.

In the summit of the dome and substantially concentric therewith is a perforation G.

Having described my invention, I claim as new and desire to secure by Letters Patent—

The design for a package-tie button as shown and described.

In testimony whereof I have hereunto affixed my signature this 3d day of January, A. D. 1901.

JOSEPH BENNOR.
